UNITED STATES PATENT OFFICE.

WILLIAM C. WINFIELD, OF WARREN, OHIO.

LIFT MECHANISM FOR LANTERN-GLOBES.

SPECIFICATION forming part of Letters Patent No. 634,077, dated October 3, 1899.

Application filed January 26, 1899. Serial No. 703,451. (No model.)

To all whom it may concern:

Be it known that I, WILLIAM C. WINFIELD, a citizen of the United States, residing at Warren, in the county of Trumbull and State of Ohio, have invented certain new and useful Improvements in Tubular Lanterns; and I do declare that the following is a full, clear, and exact description of the invention, which will enable others skilled in the art to which it applies to make and use the same.

My invention relates to a tubular lantern having mechanism for raising the globe for convenience of lighting the lantern, all substantially as shown and described, and particularly pointed out in the claims.

In the accompanying drawings, Figure 1 is a plan elevation of the lantern, showing part of the lower portion of the globe and adjacent mechanism broken away. Fig. 2 is a cross-section on line 2 2, Fig. 1, looking upward and showing in full and dotted lines, respectively, the position of the actuating mechanism when the globe is being raised and lowered. Fig. 3 is an enlarged cross-section of the globe-plate and the arm thereon.

A represents the usual tubular frame, and the globe-frame comprises the side wires B and globe-supporting plate C and canopy D, to which said wires are attached. In this instance the side wires B are rigid with plate C and pivotally or loosely connected with canopy D.

In this class of lanterns it is both convenient and desirable to have means for raising and lowering the globe for the purpose of lighting, and various means have been resorted to by inventors and manufacturers having this object in view, some engaging the globe-frame at the bottom and others at the top, suitable loops or keepers a being usually placed on the tubes A to confine and guide the globe-frame in its up and down movements.

Now in order to lift and lower the globe E and its frame together and to assure an easy movement thereof, as well as to promote a locking tendency in the mechanism at each end of the movement, I employ an elbow-lever F, pivoted on one of the tubes A and having a handle portion 2 outside and a lifting-finger 3 inside engaged with an arm G.

This arm may be a single piece, as here shown, with an eye at its center to be engaged within the edge of the eye in the globe-supporting plate, as is most clearly seen in Fig. 3, or it may be of any equivalent form and engaged in any sufficient way, the purpose being in any event to give a firm but free support to said arm on said plate, whereby the arm is made to serve all the purposes of a lift and yet is free to turn horizontally in its support to adapt it to the rotary movements of lever F.

Broadly, therefore, the invention comprises a horizontally-rotatable arm on the globe-frame engaged by a lifting-lever on the stationary portion of the lantern.

Auxiliary to the foregoing mechanism is the wire spring H, fixed at one end 4 to the globe-plate C and at the other end 5 to the arm G and serving to promote easy movement both in lifting and lowering the globe and the holding of the globe in both its up and its down positions. For example, when lever F has passed its horizontal position in raising the globe the spring comes into action to assist the lift; and its whole tendency thereafter is to keep the globe up. Hence lever F does not need to swing past a vertical position or to be provided with a lock of some kind to keep the globe raised. So, also, when the globe is being lowered after the horizontal position of lever F is again passed the spring works to seat the globe, and its normal action and effect is to keep the globe down. Altogether, therefore, a spring is a very useful and desirable element in this connection.

The arm G has a downward portion g, in or with which the rotating lever F has pivotal connection. This or any other shape of lever which will serve the same purpose may be used with the arm G. Of course the arm and lever will work alone and without the spring, but with nothing like as satisfactory results.

Manifestly either the style of spring shown or any suitable equivalent thereof may be used, and it may be connected up in any available way.

What I claim is—

1. The tubular frame and the globe-frame, a lift-lever pivoted on the tubular frame and a rigid member on the globe-frame and hori-

zontally movable in respect thereto, and connections between the said lift-lever and the said rigid member, substantially as described.

2. In a lantern, the main frame, and a rotatable lever pivoted thereon, in combination with the globe-frame and a rigid arm on the bottom of said frame free to be turned horizontally thereon and connected at its outer end with the said lever, substantially as described.

3. The tubular frame and the crank-lever thereon, in combination with the globe-frame adapted to be raised and lowered, the rigid arm horizontally rotatable on the globe-frame and a spring connected with said arm to supplement the work of the lever in raising the

globe and serving as a lock, substantially as described.

4. The lantern-frame and the crank-lever pivoted thereon, the globe-frame having a globe-supporting plate, a horizontally-rotatable arm loosely engaged on said plate, and a spring connecting said arm and plate, the said crank-lever and rotatable arm being operatively connected, substantially as described. 25

Witness my hand to the foregoing specification this 12th day of January, 1899.

WILLIAM C. WINFIELD.
